UNITED STATES PATENT OFFICE.

JULIUS GROSSMANN, OF WESTCHESTER, NEW YORK.

LOCK.

1,107,297.

Specification of Letters Patent. Patented Aug. 18, 1914.

Application filed May 20, 1913. Serial No. 768,718.

To all whom it may concern:

Be it known that I, JULIUS GROSSMANN, a citizen of the United States, and resident of Westchester, borough of the Bronx, city, 5 county, and State of New York, have invented certain new and useful Improvements in Locks, of which the following is a specification.

My invention relates to locks and has for 10 its object to provide a lock which is reliable in action and not easily tampered with by unauthorized persons and which is simple in construction and readily operated under intended conditions.

15 My improvement further contemplates the provision of a lock which will afford a protection against the door on which it is used being accidentally left unlocked, and which will further practically eliminate the 20 possibility of the leaving behind of the key necessary to operate the said lock.

Other objects of my invention will appear from the description hereinafter and the features of novelty will be pointed out in 25 the appended claims.

Reference is to be had to accompanying drawings which illustrate one specific example of my idea and in which—

Figure 1 is a face view of my improved 30 lock and coöperating parts in position on the door and door frame; Fig. 2 is a plan view thereof showing the door and frame in section; Fig. 3 is a horizontal section on the line 3—3 of Fig. 1; Fig. 4 is an inside face 35 view of the lock with the cover-plate removed; Fig. 5 is a section on the line 5—5 of Fig. 1 and Fig. 6 is a detail face view of one of the parts of said lock.

In the drawings 10 represents a door and 40 11 the door jamb, said door being provided with a suitable opening 12 for the accommodation of a tumbler barrel or cylinder 13 which may be of any suitable construction and which may contain tumbler mechanism 45 of any known type. The said cylinder 13 is secured in operative position in any convenient way as for instance by means of screws 14 coöperating with a plate 15 and lugs 16, the latter being secured to or forming part 50 of the cylinder or barrel 13. The lock further comprises the usual casing 17 secured in proper position on the inside of the door in any suitable manner as by screws 18 and having the usual removable cover plate 19 55 shown best in Fig. 3. The one end portion 20 of the said casing is extended so as to

project over the free edge of the door for a considerable distance from the inside, the said portion 20 being countersunk so as to be flush with the edge surface of said door 60 and being suitably secured thereto. With this construction the casing 17 is firmly and rigidly fastened in place on the door and is not readily pried or otherwise forced loose therefrom. The said end portion 20 of the casing 17 is provided with a suitable aperture for the accommodation of a latch 21 rigidly carried by rods 22 slidably mounted in a plate 23 which is preferably loosely positioned between grooved stationary lugs 70 24 forming part of or secured to the casing 17. The said plate 23 also forms a bearing for one end of springs 25 which surround the rods 22 and also bear against the latch 21 and serve to maintain and return the same to its operative or shot position and at the same time maintain said plate against said lugs 24 as will be apparent from an inspection of Fig. 4. The rods 22 are further provided with projections 26 which in the assembled condition 75 of the lock are engaged by preferably T-shaped plates 27 and 28 located respectively on opposite sides of said rods 22 as shown best in Fig. 3. The plate 27 is secured to a member 29 rotatably mounted in the casing 80 17 and held against axial movement in one direction by means of a flange 30, the said member 29 having an angular portion 31 and a screw-threaded end 32 the purpose of which will be described more fully later 85 on. The plate 28 forms part of a sleeve 33 rotatably mounted in the cover-plate 19 and provided with an axial opening 34 of angular cross-section through which projects a stem 35 of similar cross-section, said 90 stem fitting said opening 34 and having its one end preferably extending from one end of the rotatable member 29. The opposite end of said stem 35 extends into an angular opening 36 formed in a rotatable collar 37 100 so as to be coupled thereto, the latter being operatively connected with the tumbler mechanism in the cylinder or barrel 13. The angular portion 31 of the member 29 is adapted to fit into a similarly formed aperture in a bolt section 38, a nut 39 coöperating with the screw-threaded end 32 to secure said bolt-section 38 in position on the portion 32. The said section 38 is pivotally 105 connected at 40 with another section 41 preferably L-shaped as shown in Figs. 1 and 6, said sections 38 and 41 together forming a 110

bolt 41^a and being cut away so as to overlap at their adjacent ends and form shoulders, the one on the section 38 being indicated as 42 in Fig. 6. The section 41 is free to swing on the pivot 40 relatively to the section 38 in an upward direction but is held against movement relatively thereto in a downward direction by means of the squared end 43 abutting against the shoulder 42 of the section 38. The section 41 is also preferably provided with a knob or handle 44 for manipulating the same relatively to the section 38, both sections when in their extended or operative condition resting in a bracket 45 forming part of or secured to the casing 17 and located adjacent to the overlapping ends or pivot of the sections 38 and 41, said bracket 45 preferably being of such width as to extend completely over said overlapping ends.

20 A keeper 46, has a plate 47 projecting for a considerable distance over the door jamb 11 from the inside and countersunk therein so as to be flush with said jamb, said plate 47 being secured in position on the jamb 11 in any suitable manner as by screws 48, this construction serving to secure the keeper firmly in position and preventing ready dislocation thereof. This keeper 46 is provided with an aperture 49 for the accommodation of the latch 21 and is further formed with an upwardly open recess 50 into which the bolt section 41 is adapted to fit when the door 10 is locked as shown in Figs. 1, 2, 3 and 5. The said keeper 46 is provided with a lug 51, the purpose of which will appear more fully farther on in the description, and is further provided with alining apertures 52 into which a pin 53 is adapted to be inserted to prevent an actuation of the bolt 41^a as will be more fully brought out hereinafter, the latch 21 being formed with an aperture 21^a, arranged to be brought into registry with a similar opening 17^a in the casing for the accommodation of said pin 53 under certain conditions. The said pin 53 is preferably secured to the casing 17 by means of a suitable flexible connection as a chain 54 in order to prevent loss thereof and may further be provided with a ring 55 through the medium of which said pin may be suspended from a hook 56 when not in active use. A hook 57 pivoted at 58 on the casing 17 may also be provided for coöperation with the knob or handle 44 to maintain the bolt section 41 in an inoperative position when this is desired. In addition to this, one of the rods 22 may be extended beyond the one end of 60 the casing 17 and connected with a handle 22^a for manually retracting the latch 21, the connection between said rod 22 and handle 22^a being preferably, such as to make said handle detachable.

65 When the door 10 is locked the parts of

the lock are in the position shown best in Fig. 3 in which condition the latch 21 is positioned in the opening 49 and the bolt 41^a is located in the recess 50. A double lock is thus secured so that even if an effort is successfully exerted from the outside to force the latch 21 backward out of the opening 49 the bolt 41^a would still effectively secure the door against opening. It will be noted that the pivot 40 is in close proximity to the free edge of the door so that any instrument which might be inserted between the door 10 and the jamb 11 for the purpose of swinging the section 41 out of the recess 50 would engage said section in close proximity to said pivot 40. A considerable leverage or force would thus be required to swing the said section 41 on its pivot 40 with the result that an effort to thus actuate the bolt to open the door would in most cases be unsuccessful. However, to absolutely prevent such unauthorized actuation of said bolt section 41 from the outside, the pin 53 is inserted into the openings 52 as shown in Figs. 2 and 5 in which position the said pin 53 bridges the recess 50 and extends above said bolt and prevents any movement thereof.

70 It will of course be understood that it is impossible to swing the bolt sections 38 and 41 as a unit unless a proper key is first inserted into the barrel or cylinder 13 as the usual tumbler mechanism therein will prevent a rotation of the member 29, stem 35 and collar 37 when the proper key is not 75 in the lock and thus prevent an actuation of the bolt 41^a as a whole. By providing the bracket 45 in the neighborhood of the pivot 40 the said bolt 41^a is firmly secured against fracture at its weakest point if an 80 attempt to jimmy or otherwise force the door should be made. That is the force exerted on said bolt 41^a in such an attempt would be taken up by the bracket 45 and the keeper 46 and would prevent breakage of the bolt. The door may, therefore, be effectively locked during the night, or such other times as unauthorized entrance is to be prevented and the occupants of the particular room or rooms are therein. Assuming that 85 the occupants of the room or rooms desire to leave the same and to lock the door, the bolt section 41 will be swung out of the recess 50, the pin 53 having first been removed and the latch 21 withdrawn from the opening 49 by means of the handle 22^a thus leaving the door free to be opened from the inside. After the door has been opened and the bolt section 41 has been released by the 90 person actuating the lock as described, the said section will immediately drop back into alinement with the section 38 into the position shown in Fig. 6 it being preferably overbalanced slightly to insure this result. In other words the normal position of the 95

110

115

120

125

130

5 bolt 41^a is as shown in solid lines in Fig. 6, with the sections 38 and 41 in alinement. If the person now leaves the said room and swings the door 10 toward its closed position, the said bolt 41^a will be brought into engagement with the lug 51 on the keeper 46. This lug is of such dimensions as to prevent the latch 21 from snapping into the recess 50 and thus prematurely locking the 10 door and preventing a reopening thereof if the necessary key should accidentally have been left behind.

10 In order to properly lock the door it is necessary to insert the proper key into the 15 barrel 13 and rotate the connected collar 37, stem 35 and member 29, an operation which will raise the combined sections 38 and 41 of the bolt 41^a above the keeper 46 and permit the door to properly close, after which the 20 latch 21 may be permitted to snap into the opening 49 and the bolt to drop into the recess 50. It will be seen that with this construction the danger of accidentally leaving behind the proper key is substantially obviated as the door cannot be locked unless said 25 key is first inserted into the barrel or cylinder 13 and manipulated to operate the lock as described. I prefer to provide a stop 17^b on the casing 17 for the purpose of limiting 30 the swinging movement of the bolt 41^a in one direction, it being understood that said stop is so located as to provide ample clearance between the bolt 41^a and keeper 46 when the bolt is swung to the dotted position 35 in Fig. 1, this clearance being sufficient to allow for any sagging of the door which may take place. This stop 17^b also prevents the bolt 41^a from being forced completely back and thus protects the tumbler mechanism against injury which might result 40 from such movement. Should it be desired to use only the latch 21 without the bolt 41^a, the section 41 may simply be swung on the pivot 40 to the dotted position shown in Fig. 45 6 and the hook 57 brought into engagement with the knob 44 to maintain said section 41 in this position. In this condition the latch 21^a is free to snap into the opening 49 and may be opened by the proper key in the 50 usual manner as the position of the bolt section 41 will not interfere therewith. If the entire lock is to be rendered inoperative so that the door may be closed without being locked the latch 21 is also simply drawn 55 back by the handle 22^a until the openings 17^a and 21^a are in registry and the pin 53 then inserted therein. In this condition of the parts, the door may be closed without being locked as will be readily apparent.

60 My improvement it will be seen provides an effective lock which is substantially incapable of being operated excepting in the intended manner and which is practically incapable of being dislocated or pried from 65 the door from the outside, this latter being

also true of the keeper plate. In addition to this, my improved lock also firmly locks the door in its closed position and prevents the same from being jimmied or otherwise forced open. The opening 49 for the latch 70 21 is preferably made somewhat larger in a vertical direction than the said latch so as to allow for any sagging or dropping of the door, such change in the positions of the door thus having no effect on the operativeness of said latch. 75

Various changes in the specific form shown and described may be made within the scope of the claims without departing from the spirit of my invention. 80

I claim:

1. A lock comprising a slidable latch, a bolt capable of being swung to and from an operative position, means operatively connecting said latch with said bolt, and key actuated mechanism connected with said means and arranged to operate the same whereby said latch is slidably moved and said bolt is simultaneously swung to an inoperative position. 90

2. A lock comprising a slidable latch, a rotatable member, a bolt secured upon said member and movable thereby in the arc of a circle, means connecting said rotatable member with said latch, and key actuated mechanism connected with said member and arranged to actuate same whereby said latch and bolt are concurrently moved to an inoperative position. 95

3. A lock comprising a casing, a member 100 rotatably mounted therein, a spring-pressed latch slidably mounted in said casing, means for connecting said latch with said member, a bolt section secured upon said member, a second bolt section pivotally secured to said 105 first named bolt section and movable relatively thereto in one direction only, and key actuated mechanism connected with said member and arranged to actuate same whereby said latch is retracted and said bolt sections are concurrently moved as a unit to an inoperative position. 110

4. A lock comprising a casing, a member 115 rotatably mounted therein, a spring-pressed latch slidably mounted in said casing, means for connecting said latch with said member, a bolt section secured upon said member, a second bolt section pivotally secured to said first named bolt section and movable relatively thereto in one direction only, a bracket 120 on said casing extending over said bolt sections adjacent to the pivot thereof when the bolt is in its operative position and key actuated mechanism connected with said member and arranged to actuate same whereby said latch is retracted and said bolt-sections 125 are concurrently moved as a unit to an inoperative position.

5. A lock comprising a casing, a rotatable member mounted therein, a bolt carried by 130

said member and movable thereby in the arc of a circle, said bolt consisting of two pivotally connected sections, one of which is movable relatively to the other in one direction, coöperating means on said sections for preventing relative movement thereof in the opposite direction, and key-actuated mechanism connected with said member and arranged to actuate same whereby said bolt is moved as a unit to an inoperative position.

6. The combination of a door and door-jamb, a keeper on said jamb provided with an aperture and with an open recess, a lock on said door comprising a latch adapted to enter the aperture of said keeper, a bolt adapted to enter the recess of said keeper, means for operatively connecting said latch and bolt and key actuated mechanism connected with said means for actuating same whereby said latch is withdrawn from said aperture and said bolt is moved out of said recess.

7. The combination of a door and door-jamb, a keeper on said jamb provided with an aperture and with an open recess and with alining openings, a lock on said door comprising a latch adapted to enter said aperture, a bolt adapted to enter said recess, means for operatively connecting said latch and bolt, key-actuated mechanism connected with said means for actuating same whereby said latch is withdrawn from said aperture and said bolt is moved out of said recess and a pin adapted to be inserted into said alining openings and bridge said recess above said bolt whereby movement thereof out of said recess is prevented.

8. The combination of a door and door-jamb, a keeper on said jamb provided with an aperture and with an open recess, a lock on said door comprising a latch adapted to enter the aperture of said keeper, a bolt adapted to enter the recess of said keeper, means for operatively connecting said latch and bolt, a projection on said keeper adapted to engage said bolt and prevent a complete closing of the door and key actuated mechanism connected with said means for actuating same.

ing same whereby said latch and bolt are moved out of engagement with said keeper to permit the door to reach its completely closed position.

9. A lock comprising a casing having an opening, a latch slidable therein and provided with an aperture adapted to be brought into registry with said opening, a handle for moving said latch to bring said opening and aperture into registry with each other, a bolt operatively connected with said latch and comprising two pivotally connected sections, one of which is movable relatively to the other in one direction only to an inoperative position, a handle on said movable section for moving it to said inoperative position, a pin adapted to be inserted into said opening and aperture whereby said latch is maintained in an inoperative position and a hook adapted to engage said bolt section handle for securing said bolt-section in its inoperative position.

10. In a lock the combination of an actuating means, a main bolt section connected therewith and movable in the arc of a circle by said actuating means, a second bolt section pivotally connected with said main bolt section and movable in one direction relatively thereto to an inoperative position, and means for maintaining said second bolt section in its inoperative position.

11. In a lock the combination of an actuating means, a main bolt section connected therewith and movable in the arc of a circle by said actuating means, a second bolt section pivotally connected with said main bolt section and movable in one direction relatively thereto to an inoperative position, and means for preventing movement of said second bolt section relatively to said main bolt section in the opposite direction.

In testimony whereof, I have hereunto set my hand in the presence of two subscribing witnesses.

JULIUS GROSSMANN.
